UNITED STATES PATENT OFFICE.

MAYER SCHULTZ, OF BAY SHORE, NEW YORK.

BOTTLE CAP OR STOPPER.

1,187,013.

Specification of Letters Patent. Patented June 13, 1916.

Application filed October 15, 1915. Serial No. 56,036.

To all whom it may concern:

Be it known that I, MAYER SCHULTZ, a citizen of the United States, residing at Bay Shore, in the county of Suffolk and State of New York, have invented certain new and useful Improvements in Bottle Caps or Stoppers; and I do hereby declare the following to be a full, clear, and exact description of the invention, such as will 5 enable others skilled in the art to which it appertains to make and use the same.

The invention relates to improvements in bottle caps or stoppers.

The object of the present invention is to 15 improve the construction of bottle caps and stoppers and to provide a simple, practical, and comparatively inexpensive bottle cap or stopper of the crown seal type capable of being readily applied to and removed from 20 the neck of a bottle and of reuse as long as desired and adapted also to have the sealing cork or disk readily replaced when necessary.

With these and other objects in view the 25 invention consists in the construction and novel combination and arrangement of parts hereinafter fully described, illustrated in the accompanying drawings and pointed out in the claim hereto appended, it being understood that various changes in the form, 30 proportion and minor details of construction may be resorted to without departing from the spirit or sacrificing any of the advantages of the invention.

35 In the drawing Figure 1 is a reverse plan view of a stopper or bottle cap constructed in accordance with this invention, Fig. 2 is a side elevation of the same, Fig. 3 is a detail view showing the cam lever in its un- 40 locked position, Fig. 4 is a detail perspective view of the inner portion of the cam lever, Fig. 5 is a transverse sectional view of the device.

Like numerals of reference designate corresponding parts in the several figures of the drawings.

In the accompanying drawing in which is illustrated the preferred embodiment of the invention, 1 designates a metallic cap constructed of suitable sheet metal and provided at its annular flange or wall 2 with resilient depending arms 3 having terminal sleeves 4 for the reception of a binding wire 5 adapted to be drawn around the neck of

a bottle by a locking cam lever 6. The cap 55 1 is equipped with the usual sealing disk or member 7 of cork or other suitable material and the flange or wall 2 is provided between the arms 3 with rounded projecting portions or lugs 8 which are adapted to 60 yieldably embrace the sealing disk or cork at the periphery thereof whereby the sealing disk or cork is securely retained in the cap and held against accidental displacement. 65

The binding wire which is of circular form is designed to be constructed of resilient material and it is provided with terminal hook shaped portions 9 extending in opposite directions and forming pintles 10 70 for engaging eyes 13 of the locking lever 6. The locking lever 6 is provided at its inner portion with spaced eyes 10 and it has cam edges 11 at the inner sides of the eyes, the cam edges being arranged to grip or engage 75 the hook shaped terminal portions of the binding wire at the bends of the hooks for drawing the binding wire inwardly tightly into engagement with the neck of a bottle or analogous receptacles when the locking lever is swung upwardly from the dotted position illustrated in Fig. 2 of the drawing to the full line position shown in said figure. The locking lever 6 is provided at its outer or upper end with a terminal resilient hook 80 14 adapted to engage a projection 15 extending upwardly from the outer face of the cap 1 at the top thereof and preferably formed by indenting the same from the interior. 90

It will be seen that the top or cap is exceedingly simple and inexpensive in construction, that it is adapted to be readily applied to and removed from the neck of a receptacle, so that it may be used over and over again and that the locking lever is adapted to be readily sprung into and out of engagement with the projection 15 for securing the stopper or cap on the receptacle and for releasing the stopper or cap when the same is to be removed. 95

What is claimed is:—

A stopper of the class described including a cap adapted to fit on the neck of a bottle or analogous receptacle and provided with 105 spaced depending arms, a binding wire carried by the arms and arranged to embrace and engage the neck of a receptacle and a

locking lever connected with the binding wire and adapted to stretch and release the same, said lever being provided with a terminal hook and adapted to be swung upwardly against the cap and the latter being provided with a lug arranged to be engaged by the said hook.

In testimony whereof I affix my signature in presence of two witnesses.

MAYER SCHULTZ.
